[57] CLAIM

The ornamental design for a display case, as shown and described.

DESCRIPTION

FIG. 1 is a perspective view of a display case showing our new design;

FIG. 2 is a top plan view thereof;

FIG. 3 is a front elevational view thereof;

FIG. 4 is a rear elevational view thereof;

FIG. 5 is a left side elevational view as seen on display the right side being a mirror image thereof;

FIG. 6 is a bottom plan view thereof;

FIG. 7 is a front elevational view of a modified form of the display case shown in FIG. 1;

FIG. 8 is a front elevational view of a modified form of the display case shown in FIG. 1; and

FIG. 9 is a left side elevational view as seen on display, the right side being a mirror image thereof.

FIG. 1.

FIG. 2.

FIG. 3.

FIG. 4.

FIG. 5.

FIG. 6.

FIG. 7.

FIG. 8.

FIG. 9.
